UNITED STATES PATENT OFFICE.

JOSEPH SACHS, OF HARTFORD, CONNECTICUT.

METER-ADAPTER.

1,194,881.

Specification of Letters Patent. Patented Aug. 15, 1916.

Application filed July 27, 1915. Serial No. 42,218.

To all whom it may concern:

Be it known that I, JOSEPH SACHS, a citizen of the United States, residing at Hartford, in the county of Hartford and State 5 of Connecticut, have invented certain new and useful Improvements in Meter-Adapters, of which the following is a specification.

This invention relates to meter-adapters, 10 the object of the invention being to provide an article of this character which is adapted to inclose or house the meter and at the same time effectually protect the wires leading thereto and without in any manner preventing 15 reading of the meter at any time, the organization being such that the adapter is locked in position against surreptitious removal by the same means which seal the meter.

20 In the drawings accompanying and forming part of the present specification I have represented in detail several of the different forms of embodiment of the invention which I will set forth in detail in the following description. I do not restrict myself to this 25 particular disclosure; I may depart therefrom in several respects within the scope of the invention defined by the claims following said description.

30 Referring to said drawings: Figure 1 is a front elevation of a meter-installation provided with a meter-adapter involving my invention and sealed in place, the intermediate portion of the box represented in said view, 35 being broken away and the ends of the box being brought together. Fig. 2 is a side elevation, and Fig. 3 a top end elevation view of the same. Fig. 4 is a front elevation of the adapter stripped of everything else 40 and shown interlocked with the box appearing in Figs. 1, 2 and 3, the cover of the box being removed. Fig. 5 is a side elevation, and Fig. 6 is an end elevation of the meter 45 adapter as viewed from the open or box-associated end. Fig. 7 is a detail view of a sealing strap. Fig. 8 is a longitudinal section on the line 8—8 of Fig. 4. Fig. 9 is a front elevation of the cover portion of a modified form of adapter. Fig. 10 is a similar view of the frame portion of said modified form of adapter, a part of the box showing and the cover of the latter being removed. Fig. 11 is a bottom plan view of said frame portion. Fig. 12 is a side elevation of the 50 lower part of the cover member. Fig. 13 is

a transverse section on the line 13—13 of Fig. 10, the cover member, however, being in position. Fig. 14 is a view of the sealing strap associated with the cover member of Fig. 9. Figs. 15, 16 and 17 are views corresponding with Figs. 1, 2 and 3 respectively of a still further construction. Fig. 18 is a front view of the cover member employed in connection with the adapter illustrated in Figs. 15 to 17 inclusive. Fig. 19 is a view 60 of the frame member mounted on the box, the cover member being removed. Fig. 20 is a bottom plan view of said frame member. Fig. 21 is a view of a sealing cap member, partly broken away and in section. Fig. 70 22 is a side elevation of the lower part of the cover member illustrated in Fig. 18, and Fig. 23 is a longitudinal section on the line 23—23 of Fig. 19, looking in the direction of the arrow, the cover member, however, 75 being in position.

Like characters refer to like parts throughout the several views.

I have shown only three of the many different forms of embodiment of the invention. 80 In these as in others, there is a casing or housing which can be considered as the meter adapter proper. This casing or housing receives entirely within it or wholly incloses the meter, there being provision for 85 reading the meter for example by forming in the casing or housing an opening or where the casing or housing has a cap by forming such opening in the cap. This casing or housing also incloses the wires which lead 90 to the meter and which may extend from a box in operative relation with the meter. This box may contain one or more electrical appliances, one of which may be a switch. The wires, therefore, extend from this box 95 to the meter and are inclosed and thus protected by the casing or housing in question. There may be instances where the box is not present but where it is, I prefer to interlock the adapter or casing or housing with the 100 box or its equivalent thus positioning the adapter and obtaining security. The adapter is effectually sealed in place by the same seal ordinarily provided for sealing the meter cover. That is the means which seal the 105 meter also seal the meter adapter or casing or housing. This casing or housing may be of simple or compound construction as will hereinafter appear. For illustration one form of it may consist merely of a shell, an- 110

other may comprise a frame or body and a cover member, while a third may be like the first or second and be equipped with a cap. The sealing means may co-operate directly or through the medium of a sealing strap or yoke with the casing or housing, while in the cap construction the sealing means preferably coact with the cap.

Referring now to Figs. 1 to 8 inclusive the numeral 2 denotes a box and 3 a meter which may be and are of well-known construction. As I have already noted the box 2 may contain one or more electrical appliances, and I have specifically mentioned a switch in this particular connection. What is inclosed, however, by the box 2 and the type or character of the meter 3 does not concern the invention. The box and the meter may, as will be inferred, be of any construction, and there may in fact be cases where the box 2 is not present, as the primary purpose of the adapter is to inclose the conductors leading to the meter, or from it for that matter, to protect such conductors and to thwart tampering with the meter especially where the wires or conductors join therewith. When the box 2 is present, it presents a convenient support for the adapter, and I prefer also to interlock the adapter with the body of the box for the reason already noted. The adapter shown in the views last mentioned is denoted in a general way by 4 and comprises parallel sides 5, front 6 and top 7, being made of suitable material such as sheet metal and of a size to freely receive the meter 3. The adapter, casing or housing 4 has in the form represented, no bottom, being open at its lower end to thus provide freely for the passage of wires from the box 2 to the meter. In the present case the open bottom of the adapter, casing or housing 4 is closed by the box 2 which has an opening in its top through which the wires in question extend. As will be inferred, I have used the terms top and bottom merely for convenience as this is the way they appear on the drawings. The arrangement might be inverted or the parts might stand horizontally or they might be vertical and be horizontally aligned, the point being that preferably the adapter should have one end closed and the opposite open. In what I have termed the front 6 there is an opening 8 and a portion of the meter 3 extends through this opening as represented in Figs. 1, 2 and 3. The projecting part of the meter is that which in the type shown is furnished with the indicating means. The adapter 4 as shown is provided with an outwardly extending wing 9 suitably fastened thereto. This wing has between its ends the bracket 10 fastened within the adapter and to the front 6 thereof, for instance, by one or more rivets 11. The box 2

has in its top the opening 12 for the wires which extend therefrom and which are connected with the meter 3. At opposite sides of the opening 12 are guideways or slide-ways 13 into which the wing 9 can be slid as shown in Figs. 4 and 8 for instance. After the box 2 and meter 3 are mounted, the adapter 4 may be positioned as follows: The cover 14 of the box 2 will be opened after which the wing 9 will be slid into the guideways 13 and the adapter, casing or housing 4 will then be fitted against the support to which the box 2 and meter 3 are connected. Following this the cover 4 will be closed and then sealed by the customary sealing means denoted in a general way by 15. At this time a part of the meter 3 will project through the opening in the adapter 4. The front 6 at opposite sides of the opening 8 has keyways, shown as elongated slots 16 in parallelism with each other and these are adapted to receive the keys or terminal portions 17 of the legs of the bail or yoke-like strap 18 which reduced or terminal portions 17 after the adapter is positioned, are inserted into the slot 16, the transverse portion of the strap extending across the face or projecting portion of the meter 3. In the transverse part of the strap 18 are perforations or holes 19 which are located to receive the sealing screws 20 constituting a part of the regular equipment of standard meters. The strap 18 is sufficiently resilient to insure the accurate insertion of its terminal 17 in the slots 16 and to bring the shoulders 21 solid against the outer face of the front 6. This positioning of the strap causes the projection of the screws 20 through the two perforations 19. After the strap 18 has been positioned and the screws 20 extended through the perforations 19, the nuts 22 will be applied to the respective screws and turned until they practically abut against the transverse portion of the strap. When this is accomplished the wire 23 will be passed through the usual perforations of the nuts 22, the ends brought together and sealed as by the seal 24. I have described a familiar type of sealing means; any other will answer the purpose as well.

In Figs. 9 to 13 I show a modified form of adapter. This adapter like the one already described is in the form of a casing or housing, but it is of compound construction comprising a frame member or portion 25, and a cover portion 26, the cover portion being adapted for interlocking connection with the box 2 or its equivalent and the frame portion having a wire-way 30 for the conductors from the box to the meter as will hereinafter more particularly appear. This adapter, casing or body may like the other, vary in shape, the invention not concerning any particular form. As shown it is also

practically rectangular. The frame portion 25 may be made up of strap metal in one piece bent to the desired outline and the ends of which may be welded, riveted or otherwise suitably connected together. The cover member 26 in outline is like the adapter shown in the form already described, although it is shallower, being intended merely to slightly overlap the outer part of the frame portion 25. The cover member, therefore, comprises a front, top and sides but is open at the bottom. Fastened by riveting or otherwise to the sides of the frame portion 25 interiorly thereof are attached 15 taching lugs as 27 perforated to receive screws or other fastenings by which the frame portion can be fastened to the support which carries the meter inclosed in said frame portion which I might note is mounted 20 so as to abut and be held against the body of the box 28. In the front of the cover member 26 is an opening 29 and through this opening a part of the meter can project or that part provided with the 25 indicator or the indicating part of the meter may be wholly back of the front of the cover member 26 in which event the opening 29 need be only of sufficient size and so located with relation to the indicating dial to 30 provide for the reading of the meter at any time. In the bottom of the frame portion or member 25 is an opening 30 which provides for the passage of wires from the box 28 to the meter inclosed in the adapter. The 35 cover member or portion 26 has a wing 31 connected as by the flange 32 with the cover member interiorly thereof by riveting or in any other suitable manner. After the frame portion or member 25 has been positioned, 40 the meter being within it and the frame member resting on the box 28, the wires will be connected up and passed through the opening 30 to the meter, the cover of the box 28 being open at this time. In the top 45 of the box is an opening 33 through which these wires extend and at opposite sides of the opening are parallel slideways 34. After the frame member 25 has been mounted and the wires run from the box to the 50 meter, the wing 31 will be slid along the guideways 34 and fitted over the frame member 25, subsequent to which the cover of the box 28 can be closed and sealed as already set forth. When this is done the 55 strap or sealing member 35 exactly like the strap or sealing member already described will be applied and then sealed. The opening 30 is at the rear of the lower wall or side being notched as at 36 to receive the 60 flange 32. It will be understood that the strap 35 is exactly like the strap 18 and is sealed in place by the meter sealing means and that the cover member 26 has slots as 65 to receive the terminals of the strap 35. Referring now to Figs. 15 to 23 inclusive.

The meter adapter shown mounted in Figs. 15, 16 and 17 is denoted in a general way by 40 and as in the case of the other adapters incloses the meter 41. This meter adapter 40 comprises a frame portion or member 42 and a cover member 43. The frame member 42 in shape is like that already described. Its lower wall or side is slotted or has an opening 45, the bridgepiece 46 crossing the slot 45 which as will be understood extends 70 entirely across said lower wall. This bridgepiece 46 is fastened within the frame member in some suitable way as by riveting. It has cut and bent from it the outwardly extending tongues 47 adapted to enter the slideways or guideways 48 at opposite sides of the wire opening 49 in the top of the body of the box 50. This frame member 42 is mounted exactly like the frame member 25 and after it is positioned the cover member 43 will be applied and the interlocking wing 51 of said cover member 43 will be introduced into the guideways 48. This cover member 43 has an opening 52, but has no strap receiving slots or equivalents. The 80 indicating portion of the meter extends through the opening 52. After the cover member 43 has been properly located and interlocked with the body of the box 50 the cap or sealing member 53 will be fitted 85 against the outer face of the front of the cover member and will receive within it the projecting portion of the meter. The cap member 53 has an opening 54 through which the indicating portion of the meter can be 90 seen. The cap member may, as will be understood, be of any suitable shape. That shown is approximately of frusto-conical form. In its top are perforations or holes 95 55 to receive the sealing screw studs of the meter and after these sealing screw studs have been passed through said holes or perforations 55 the nuts 56 will be applied to the screw studs and turned until they abut against the top of the cap member or practically so, thus clamping the cap member 53 against the cover member 43. When this is accomplished, the wire 57 will be passed through the perforations of the sealing nuts, the ends brought together and sealed as by 100 the seal 58. When the seal 58 is applied it acts, therefore, not only to seal the meter but to seal the adapter, and this is accomplished by means of the cap member 53 being held in place between the nuts 56 and the cover member 43, thus subserving the same function as is accomplished by the sealing strap 18 when the same is positioned as shown for illustration in Figs. 1 and 2. The cap 53, however, furthermore serves to 105 actually inclose that part of the meter which would remain exposed where merely the sealing strap 18 or its equivalent were used. It will be clear that when the meter adapter of my invention is to serve its meter 110

115

120

125

130

protective purpose without having associated therewith a sealable box from which the wires may be extended to and pass into the adapter casing, the opening through which the wires pass into and from the adapter casing will in such instances be of a suitable shape and size for the connection of the proper wire carrying pipes or conduits. An important feature of the particular embodiments of my invention here shown is the fact that one size of casing may serve universally for a number of different meters, although these may vary in height and even form. To accommodate meters having round bodies of different diameters or rectangular bodies, it is simply necessary to correspondingly perforate the front of the casing to allow for the varying heights of the meter beyond or above the face or front of the casing and to provide correspondingly sized sealing straps or caps.

What I claim is:

1. A meter adapter for use in connection with meter installations, in the form of a casing for receiving the meter and means for directly sealing the meter, said sealing means also sealing the adapter.

2. A meter adapter for use in connection with meter installations, in the form of a casing for receiving a meter, and means for sealing the cover of the meter against removal, said sealing means also sealing the adapter.

3. A meter adapter for use in connection with meter installations, to receive the meter and means for sealing the meter, the meter sealing means also holding the adapter to its support in protective relation to the meter.

4. A meter adapter for use in connection with meter installations, in the form of a casing for receiving the meter and having means whereby the meter sealing means can seal the casing and the latter having means for interlocking connection with a box constituting a part of such installation.

5. A meter adapter for use in connection with meter installations, in the form of a casing for receiving the meter and having means whereby the meter sealing means can seal the casing, the latter having a wing to interlock with a box constituting a part of said installation.

6. A meter adapter for use in connection with meter installations, in the form of a casing having a front, sides and one end, the other end of the casing being open and means for directly sealing a meter, said meter sealing means also sealing the adapter.

7. A meter adapter for use in connection with meter installations, in the form of a casing comprising a frame member and a cover member for the frame member, the casing being adapted to inclose the meter, and the cover member having means for

interlocking connection with a box constituting part of the meter installation.

8. A meter adapter for use in connection with meter installations, in the form of a casing comprising a frame member and a cover member for the frame member, the casing being adapted to inclose the meter and the cover member having means for interlocking connection with a box constituting part of the meter installation, and means for sealing the meter and the casing.

9. A meter adapter to receive a meter, and a strap to extend across the meter, connected with the adapter and in sealed connection with the meter, whereby the strap will hold the meter adapter in place when the meter is sealed.

10. A meter adapter for use in connection with meter installations, in the form of a casing for receiving the meter, having slots, a strap to extend into said slots, and means for sealing the strap to the meter.

11. A meter adapter for use in connection with meter installations, in the form of a casing for receiving the meter, and a sealing member connectible with the casing, and meter sealing means for sealing the sealing member.

12. A meter adapter to receive a meter, a member to bridge the exposed portion of the meter and terminally connected with the adapter, and means for sealing said bridging member to the meter when the latter is in operative relation.

13. A meter adapter to receive a portion of a meter for protective purposes, a bridging member crossing that part of the meter outside of the adapter, and means whereby said bridging member is sealed by the same means that seal the meter.

14. A meter adapter comprising a casing into which a part of the meter projects, a member bridging across the meter and in sealed connection with the adapter.

15. A meter adapter comprising a protective casing for inclosing a portion of a meter, and means interlocking said meter and adapter casing and holding the same in sealed relation.

16. A meter adapter comprising a casing inclosing a part of a meter for protective purposes, a U-shaped strap, straddling the meter and connected at its ends with the adapter casing, a cross bar of the U-shaped strap being provided with means whereby it may be sealed in position for thus holding the casing in its protective relation to the meter by the same means that seals the meter.

17. A meter adapter casing provided with means for its connection to a box and adapted to receive a part of a meter for protective purposes, and a sealing element in the form of a bar passing across the face of the meter and adapted to hold said

adapter in protective coöperative relation with said meter by the same sealing means that seal the meter.

18. A meter adapter casing adapted to receive a part of a meter for protective purposes, and a sealing element in the form of a bar passing across the face of the meter and adapter to hold said adapter in protective coöperative relation with said meter

by the same sealing means that seal the meter.

In testimony whereof I affix my signature in presence of two witnesses.

JOSEPH SACHS.
